(57) **CLAIM**

The ornamental design for a tire for automobile, as shown and described.

DESCRIPTION

FIG. 1 is a front, left perspective view of a tire for automobile showing our new design;

FIG. 2 is a front view thereof;

FIG. 3 is a left side view thereof;

FIG. 4 is a right side view thereof;

FIG. 5 is a rear view thereof; and,

FIG. 6 is a partial enlarged view of FIG. 2.

The top view and the bottom view are the same as the front view.

The broken lines shown in FIG. 6 illustrate the boundaries of the figure and form no part of the claimed design.

1 Claim, 6 Drawing Sheets
